UNITED STATES PATENT OFFICE.

NICOLAS BENOIT GRILLET, OF NEUILLY, FRANCE, ASSIGNOR TO SOCIETE CHIMIQUE
DES USINES DU RHONE, OF PARIS, FRANCE.

PROCESS OF MANUFACTURE OF CELLULOSE ESTERS OR ETHERS IN A SOLVENT.

Application filed November 22, 1924. Serial No. 751,458.

To all whom it may concern:

Be it known that I, NICOLAS BENOIT GRILLET, residing at Neuilly, Seine, France, a citizen of the Republic of France, have invented certain new and useful Improvements in Processes of Manufacture of Cellulose Esters or Ethers in a Solvent, of which the following is a specification.

It is known that, in the etherification and esterification of cellulose in a liquid medium, it is not sufficient to treat the cellulose by just the quantity of reagents necessary for the reaction, for if such was the case, a very thick product would be obtained, which 10 it would be practically impossible to stir, when energetic stirring is absolutely necessary, not only to allow of the heat generated by the reaction being properly dissipated, but also to ensure that the reaction is performed in the whole mass in a manner as 15 homogeneous as possible.

In order to obviate this drawback, in all the processes used for the etherification and the esterification of cellulose in a liquid 20 medium, a proportionally large amount of a diluent suitable for use is added to the reacting mass, for instance, six times the weight of the cellulose acted upon, or even more.

This diluent may consist of an excess of the necessary reagents, but, in the processes usually adopted, and to which the present invention refers more specially, a solvent of the ether or ester of the cellulose manufactured is selected as a diluent. In this manner, the mass under treatment is, as a matter of fact, thick at the beginning of the reaction, but, as the latter proceeds, the mass becomes more fluid, to become finally 30 a more or less viscous fluid.

Unless a very large proportional amount of solvent is used, which would be costly, it is nevertheless necessary, because of the first (thick) phase of the reaction, to use 40 apparatus provided with very powerful stirring devices, for instance, mixers of the type Werner-Pfleiderer ("Chimie et Industrie," 1920, Vol. I, page 600).

These apparatus are costly and absorb 50 much power. Unless their mixing members are of unusually large dimensions, they can only deal in one operation with relatively small quantities of cellulose, 200 to 300 kilogrammes, for example. Finally, the use of

mixers or of baffles used in connection therewith entails the presence in the apparatus of corners with deficient stirring where cellulose accumulates which escapes more or less completely from the reaction, and soils the final product.

Applicant has discovered that all these difficulties are overcome, and this even with an economy of solvent, by conducting the etherification and esterification of cellulose in rotary apparatus, with or without internal balls, rolls, rollers, or the like, in order to enhance the internal stirring and preferably driven from their periphery, so that they do not contain inside any shaft or other supporting or driving members.

In the drawings accompanying and forming part of this specification

Fig. 1 is a longitudinal sectional view of a form of apparatus constructed in accordance with the present invention; and

Fig. 2 is a transverse section thereof.

Referring to the drawings *a* is a cylindrical container provided with peripheral rails *b b* resting on rollers *c c* and driven round by a toothed wheel *d* engaging a peripheral rack *e*. The container is cooled or heated by means of the sprayer *f*. A manhole *g* and a drainage aperture *h* are provided, and also sampling pipes *k k*.

Apparatus such as that above described are free from any corner where cellulose could escape from the reaction.

It is, on the other hand, practically easy to give to such apparatus such large dimensions as may be desired, for instance, ten or twenty meters cubed or even more, so as to treat in one operation 1,000 kilogrammes of cellulose or more. In this way installation costs, as well as the power consumed and the cost of manufacture and of supervision, are reduced. Moreover, large amounts of cellulose derivatives, perfectly homogeneous, are thus obtained, which is of great importance for their ultimate use, for instance, for the manufacture of threads, films or plastic bodies. Such a result could only be obtained very imperfectly before, by mixing products of several independent etherifications or esterifications.

Finally, it is possible to reduce in very noticeable proportions the quantity of solvent employed, for example, to 2 or 3 times only the weight of cellulose, while neverthe-

less obtaining a regular and homogeneous reaction.

It is understood that one can give to the rotary apparatus forming the object of the invention any form suitable in view of the result sought, cylindrical, spherical or other. For example, they may have the shape of a cylinder, with a horizontal or oblique axis, rolling on its side upon rollers, or by means of 5 gearings or of any other suitable devices. The internal stirring will be enhanced by selecting rather a flat shape and a large diameter. Moreover, by varying the speed of rotation, as well as the number and weight of the 10 balls, rolls, rollers and the like, *m*, introduced into the apparatus, it will be understood that a sufficient stirring can be obtained in all cases.

The apparatus are cooled externally by 20 any suitable process. For instance, their lower portion may dip into a trough filled with cold water or brine, or else their walls may be sprayed, by means of suitably disposed perforated pipes, with cold water or 25 brine, or both methods may be used simultaneously. Naturally the form of the apparatus, its speed of rotation, and the amount and temperature of the cooling water or brine will be chosen so as to ensure as much 30 as may be needed the dissipation of the heat generated during the reaction. On the contrary, by substituting hot for cold water, the same arrangement may be utilized to supply heat to the reacting mass.

35 Finally, the apparatus will be provided with any accessory or desired devices, such as inspection windows, manholes, or charging openings; sampling arrangements, drainage cocks, etc., the installation of 40 which does not present any difficulty.

Particularly, the charging may take place 45 in a convenient manner by a manhole provided in the side of the apparatus and brought to the top to the level of a charging platform. The emptying may be performed by gravitation through the same aperture or by a special cock, brought to the lowest 50 position underneath, after, if necessary, removing the cooling trough. It can also take place by decanting, by means of a removable pipe introduced inside the apparatus by any aperture brought to the top.

What I claim and desire to secure by Letters Patent is:—

1. A process of esterifying cellulose, which 55 consists in executing the reaction in the presence of a liquid solvent of the desired product in a comparatively large closed vessel, and rotating said vessel thereby to agitate the mixture.

60 2. A process of esterifying cellulose, which consists in executing the reaction in the presence of a liquid solvent of the desired product in a comparatively large closed vessel, placing in said vessel loose members, 65 and rotating said vessel thereby to cause said members to roll around and agitate the mixture.

70 3. A process of esterifying cellulose, which consists in executing the reaction in the presence of a liquid solvent of the desired product in a comparatively large closed vessel, rotating said vessel thereby to agitate the mixture, and cooling the vessel during 75 rotation.

75 4. A process of esterifying cellulose, which consists in executing the reaction in the presence of a liquid solvent of the desired product, the proportions by weight of said solvent to the cellulose being approximately 80 2 to 3, in a comparatively large closed vessel, and rotating said vessel thereby to agitate the mixture.

85 5. A process of esterifying cellulose, which consists in executing the reaction in the presence of a liquid solvent of the desired product, the proportions by weight of the solvent to the cellulose being approximately 90 2 to 3, in a closed vessel in sufficient quantity to occupy 30 to 50 per cent of the 95 capacity of the vessel, and rotating the vessel thereby to agitate the mixture.

95 6. A process of acetylating cellulose, which consists in executing the reaction in the presence of a liquid solvent of the desired product, the proportions by weight of the solvent to the cellulose being approximately 100 2 to 3, in a closed vessel in sufficient quantity to occupy 30 to 50 per cent of the capacity of the vessel, and rotating the vessel, thereby to agitate the mixture.

In testimony whereof I affix my signature.

NICOLAS BENOIT GRILLET.
